United States Patent

Des. 236,643
Patented Sept. 2, 1975

236,643

FLORAL BOUQUET HOLDER OR SIMILAR ARTICLE

Edward W. Ross, Medinah, Ill., assignor to Floralife, Inc., Chicago, Ill.

Filed Apr. 4, 1974, Ser. No. 457,965

Term of patent 14 years

Int. Cl. D11—02

U.S. Cl. D35—3 R

FIG. 1 is a side elevational view of a floral bouquet holder or similar article showing my new design;

FIG. 2 is a front elevational view;

FIG. 3 is a rear elevational view;

FIG. 4 is a bottom plan view; and

FIG. 5 is a top plan view.

I claim:

The ornamental design for a floral bouquet holder or similar article, as shown.
